BOTTLE CAPPING MACHINE

Rudolf W. von Sydow and Edward J. McCoy,
Saginaw, Mich., assignors to Apex Paper Products Corporation, Saginaw, Mich., a corporation of Michigan

Application October 26, 1932, Serial No. 639,644

6 Claims. (Cl. 226—92)

This invention relates to bottle capping mechanisms. It pertains to a new and useful cap affixing device that can be used as an attachment for a bottle filling machine, or it may be embodied in a separate machine.

In our co-pending application, Serial No. 599,468, there is shown and described a bottle cap of heavy paper, blanked out and pressed to present a central flat disk portion surrounded by a peripheral flange of inverted U-shaped cross section. Such a cap provides a seal around the annular shoulder which is inside of the neck, and also seals around the exterior surface of the bead at the mouth of the bottle.

The present invention has for its general object to provide feeding and affixing mechanism for caps of such character, that shall be simple in construction, having few working parts and shall be positive and reliable in action and, without any special adjustment, capable of handling caps of different thicknesses, performing its work very rapidly and with uniform accuracy and precision under all conditions of commercial use.

The invention also includes a number of new and useful structural features by which the various steps of a cap affixing operation are performed. Among such novel collateral features are the following:

An arrangement whereby the supply stack of caps and also the devices for releasing caps from the stack are kept from undesirable shaking or jarring, so that the caps can be fed out one at a time with certainty and are correctly positioned on the bottle mouths regardless of ordinary manufacturing variations in the shape, size and thickness of the caps. The cap release mechanism includes a novel retarding means whereby each cap is tilted as it is released from the stack so as to fall flatwise on the guideway leading to the cap affixing zone.

A stationary cap guiding member, preferably a chute, a trough, or its equivalent, employed to direct the caps from the stationary container to the bottle, is also utilized to provide the above mentioned rigid support for the container and the cap releasing mechanism which is mounted on the wall of the container.

The claimed invention includes a novel stop device of simple construction whose function is to halt the cap as it leaves the guide member and to cause each cap to drop fairly onto the bottle mouth. The vertically reciprocating capping plunger is provided with an improved yieldable mounting to enable the plunger to cap bottles of variant heights without any manual adjustment of the machine.

The operating principle involved in the present invention is that of a machine which delivers caps one at a time from a stationary supply stack in such a way that one edge of the cap is released from the stack slightly in advance of its diametrically opposite edge, thus delivering the cap in a tilted position to a downwardly inclined guideway, along which it slides by gravity, or else, in a modified embodiment, is propelled by mechanical means to a position above the bottle mouth. There the cap is halted by a suitable stop and is constrained to drop freely and land fairly upon the beaded mouth of a bottle in readiness to be pressed into sealed position by the capping plunger.

In the appended claims we have pointed out the essential elements of our invention, it being understood, however, that the claims are not intended to be limited to the form of the parts illustrated and described further than a limitation to the described form is necessary to distinguish them from the prior art.

Like reference characters indicate like parts in all figures of the drawings.

Fig. 1 is an isometric view of the invention as it appears when employed as an attachment for a known bottle filling machine adapted to cap two bottles at a time, the working parts of the capping mechanism being shown in duplicate. In this preferred embodiment there is shown a gravity guideway or chute which feeds the caps to the zone of the capping plunger. The bottle filling machine is not shown, except its known vertically reciprocable cross-head that actuates the capping plunger.

Fig. 2 is a vertical sectional view taken on the line 2—2 of Fig. 1, showing the plunger raised and a cap in the act of being delivered from the container.

Fig. 3 is a similar view showing the plunger in its cap affixing position, the supply of caps being held in the container.

Fig. 4 is an enlarged fragmentary detail showing a face view of a part of the cap-releasing device, viewed in the direction of the arrow in Fig. 3, 45 the cap-supporting finger being removed.

Fig. 5 is a sectional view taken on line 5—5 of Fig. 4.

Fig. 6 is a part sectional view showing the invention in a modified form, employing mechanical means instead of a gravity chute for impelling the released caps from the end of the guide member.

The preferred embodiment is illustrated in Figs. 1, 2, 3, where numeral 1 designates a vertically reciprocating plunger that is actuated by a cross-

head 2 on a vertically reciprocatory drive rod 3, or else to any other appropriate part of a bottle filling machine (not shown) if the invention is to be employed as an attachment for a bottle filler; or rod 3 may represent any suitable power driven member of a capping machine which is independent of a bottle filler. Spring cushioning means 4 on the stem 1a of the plunger below the cross-head 2 serve to limit the pressing force that can be applied to the bottle cap during the down stroke of the cross-head in order to prevent breaking any bottles that are oversize or unusually tall. A second spring, 5, on the stem 1a between cross-head 2 and a shoulder 1b on the upper end of the plunger stem 1a serves to yieldingly lift the plunger 1 when cross-head 2 moves upward.

A stationary container 6, holding a supply of stacked caps 7, is located preferably somewhat higher than plunger 1 and remote from it, as shown, to permit the cap to feed downward by gravity to the cap affixing station.

The cap container, being stationary and rigid, is distinguished functionally from earlier hoppers that reciprocated vertically during the capping operation and consequently jarred the stack of caps, sometimes interfering with their proper delivery. Stationary container 6 constitutes a rigid base or support for the cap-releasing mechanism and prevents it from becoming disarranged or misadjusted, assuring precision in its operation. Moreover, the cap releasing mechanism is located so that its actions can readily be timed in with capping plunger 1. Guideway 8 extends downwardly from the container and then laterally, preferably in a horizontal direction, at 8a, toward the path of travel of plunger 1. The guide may be in the form of a toboggan-like trough, shown in Fig. 1, or a drop-and-slicer feed, as in Fig. 6. The guide preferably is integral with the container 6 or else is firmly secured to it, and constitutes a rigid support. The lower part of guide 8 is horizontal and terminates adjacent to the working zone of plunger 1, so that a cap sliding freely down the guide 8 will leave the end 8a and project itself across the path of travel of the plunger.

Appropriate stop means, as wall 9, halts the projected lateral flight of the cap just after it leaves the delivery end 8a of the guideway 8 and compels the cap to drop fairly upon the rim of the bottle mouth ready to be pressed into place by a subsequent action of the cap affixing plunger 1.

The cap releasing device may be of any suitable type without departing from the scope of the invention as defined in certain of the claims, but the structure illustrated is deemed to be preferable and in itself embodies certain new and useful claimed features. As shown in Figs. 2 to 5 there are two cap engaging elements mounted on the wall of the fixed container 6 and positioned near its bottom end opposite guideway 8. Of these elements, yieldable finger 10 has only in-and-out movement, the other element, claw 11, having in-and-out and also up-and-down movements.

Projection 12 on the wall of container 6 is provided for tilting and retarding an edge of each cap so it will travel edge foremost along the guideway from the stack onto the bottle after having been released by finger 10.

The means for retracting finger 10, also the means for moving claw 11 lengthwise of the container while causing it first to grip and then release the stack of caps, are shown in their pre-

ferred form in Figs. 2 to 5. A wall of container 6 is formed with a longitudinal slit-like aperture 13 near its bottom and above the aperture at 6a the wall is beveled exteriorly. A plate 14 fixed to container 6 overlies the beveled portion 6a. It is formed to present a channel 14a for strap 11a. Finger 10, which is made of resilient metal, is secured at one end to the plate 14 and about midway of its length there is an inward cam-shaped projection 15.

Finger 10 provides a temporary rest for one edge of the cap while the opposite edge is being supported by projection 12 which is rounded as shown in Fig. 3. Finger 10, when withdrawn as in Fig. 2, releases the bottom cap 7a from the stack. Being for the moment retarded by projection 12, the cap 7a tilts as it falls onto the inclined guideway 8.

The longitudinally movable flexible metal strap 11a lies against the wall of container 6 and slides through channel 14a of plate 14. Strap 11a is bifurcated at its lower end, being formed with a central longitudinal slit 11b. The ends of the bifurcations are bent inwardly to provide cap engaging claws 11, 11. A cross bar 11c is fixed on the outer face of each bifurcation, its upper edge 11d being cam shaped so as to engage cam 15 on finger 10, and thereby withdraw the finger from container 6 and releasing a cap when strap 11a is pulled upward, as in Fig. 2.

Two cams 16, 16, Figs. 4 and 5, are provided on the outer faces of the bifurcations. When strap 11a is drawn upwardly cams 16 enter channel 14a of plate 14 and by wedging action therein the cams force the flexible strap 11a to bend, as shown in Fig. 2, so as to seat itself flat against the beveled face 6a of the wall of the container. The extremities of claw 11, while moving upward are thus forced into the container and seize the marginal edge, or the outer peripheral wall, of the next-to-bottom cap 7b, push it against the opposite wall of the container at 17 and thus temporarily support the stack. Cam 11d meanwhile, by its engagement with cam 15, withdraws finger 10 and releases the lowermost cap 7a, which, being slightly retarded by projection 12, tilts and then drops, landing flatwise upon inclined chute 8, as is shown in Figs. 2 and 3.

When the strap 11a reverses its direction and begins to move downward by gravity due to its own weight and the weight of the superimposed caps its cam 11d releases finger 10 which projects itself into the container, as shown in Fig. 3. Cam 16, on strap 11a, moves down out of the channel 14a in bar 14, permitting strap 11a to straighten, whereupon claw 11 releases the cap 7b which it had been holding. The stack of caps then settles down to temporarily rest on finger 10 and projection 12. The operation is repeated to deliver each succeeding cap.

The requisite alternating upward and downward movements of strap 11a are effected as follows:

At the upper end of strap 11a is a boss 18 having a recess 18a in which the end of a trigger member 19 is loosely received. Trigger 19, pivoted at 20 to a fixed support as container 6, is arranged so that its outer free cam-shaped end 19a shall be appropriately contacted by a yieldable wiper 21 as it moves up with cross-head 2, and its top edge is contacted by 21 on its down stroke, as shown in Fig. 2, or with any other suitably moving part in timed relation with the strokes of the capping plunger 1.

Referring now to the alternative structure, Fig. 75

6, numeral 22 designates a horizontal guide or chute, 23 is a sliding feeder plate having its end 23a shaped to fit the rim of a bottle cap, and 24 is a bell crank lever joined at one end by pin 5 and slot connection 24a to plate 23. Lever 24 is pivoted at 24b to a fixed support, as housing 6, and its upper end 24c is received in an elongated slot 25 of a vertically movable bar 26 which is carried by cross-head 2. Slot 25 has its end walls 10 positioned so as to suitably abut and actuate the bell crank lever and feeder plate 23.

Strap 11a has a projection 27 which is engaged by stop members 28, 28a on a bar 29 that moves up and down with cross-head 2, for actuating the 15 release mechanism.

Each released cap drops upon plate 23, as shown in Fig. 6. The plate is then driven to the right by the bell crank lever 24 and bar 26 and the cap drops into trough 22. Plate 23 then travels to the left and engages the cap in its recessed end 23a and projects it part way across the zone 20 of action of the plunger, where it is halted by stop 9 and drops squarely upon the bottle neck.

Occasionally caps are supplied which are 25 thicker or thinner than ordinary. They may even be inaccurate in size, may have various degrees of surface roughness, or may vary in shape due to slight warping that sometimes occurs while they are in storage. The capping device herein 30 described will operate satisfactorily regardless of such variations.

Having thus described our invention, what we 35 claim and desire to secure by Letters Patent is:

1. A bottle capping machine including a vertically reciprocating plunger and having, in combination, a container for a supply of caps that are 40 stacked flatwise, the stack being located on a fixed support higher than the plunger, a continuous guideway extending downwardly and thence laterally in a horizontal direction from the container to a place adjacent the zone of travel of the plunger, cap releasing means associated with the container and including cam-actuated cap 45 grippers and an opposed cap-engaging projection co-operating with said grippers, said releasing means being operable to deliver from the container to said guideway one cap at a time, actuating mechanism for said releasing means operable in timed relation to said plunger, a stop member positioned to be engaged by a cap upon leaving the lower horizontal end of said guideway, said stop member being arranged to constrain said cap to drop straight down flatwise and thereby seat itself upon the rim of a bottle 50 mouth which is located in the path of travel of the plunger.

2. A bottle capping machine including a vertically reciprocating capping plunger having, in combination, a stationary container positioned 55 remote from the zone of operation of the plunger, cap releasing means operable to deliver one cap at a time from said container in appropriate

timed relation to the operations of the plunger, said releasing means including an abutment positioned to be releasably engaged by an edge of a cap being delivered from the container, whereby the cap upon release is caused to tilt, a guideway extending downwardly at an incline from the container and leading to the zone of action of the plunger, and stop means arranged to engage the cap upon leaving said guideway and serving to direct the cap onto a bottle positioned in the path 10 of travel of the plunger. 5

3. A bottle capping machine having a reciprocating cap applying plunger and including in combination a stationary container for a supply of bottle caps, a cap release device operatively 15 associated with the container, actuating means for said release device operable in timed relation with said plunger, cap tilting means associated with the container and adapted to tilt each cap upon its release, and a guide element arranged 20 to conduct such tilted released caps by gravity to the zone of travel of said plunger.

4. A bottle capping machine including in combination, a fixed container for a stack of caps, provided with an outlet at its lower end, a fixed 25 horizontal guideway spaced below said outlet, a reciprocating sliding feeder plate mounted on said guideway, a cap-retaining spring finger mounted on a wall of said container and normally urged into cap-retaining position, a fixed cap- 30 retarding projection on the container opposite said finger, a cross-bar movable lengthwise of the container adapted to effect movement of said finger to release position, and means for actuating said horizontal feeder plate and said cross-bar 35 in timed relation.

5. In a cap applying machine a stationary cap container formed with a longitudinal aperture near its lower end and an exteriorly beveled portion above said aperture, a finger mounted on 40 a fixed support and normally held in the aperture in cap-engaging position, a cam-shaped projection on said finger, a flexible strap longitudinally reciprocable on the container and having a cam-shaped element adapted to engage the projection on said finger, a second cam on said strap, 45 a fixed plate member opposite said beveled portion and formed with a channel to slidably receive said second cam whereby the strap is flexed and forced against the said beveled portion. 50

6. A capping machine including a reciprocating plunger and having in combination a container for a stack of caps, said container being mounted on a fixed support, a cap delivery device arranged to release one edge of the endmost cap of said 55 stack slightly in advance of its diametrically opposite edge, whereby each cap is delivered in a tilted position, and a guideway for receiving the cap, arranged to deliver it to the zone of action of the plunger, for the purposes set forth. 60
